Primary Examiner — Sandra Snapp*Assistant Examiner* — Anehita E. Oribabor(74) *Attorney, Agent, or Firm* — Rankin, Hill & Clark LLP(57) **CLAIM**

The ornamental design for a susceptor as shown and described.

DESCRIPTION

FIG. 1 is a perspective view of a susceptor showing my new design

FIG. 2 is a front elevational view thereof,

FIG. 3 is a rear elevational view thereof,

FIG. 4 is a left side elevational view thereof,

FIG. 5 is a right side elevational view thereof,

FIG. 6 is a top plan view thereof,

FIG. 7 is a bottom plan view thereof; and,

FIG. 8 is an enlarged partial cross-sectional view taken along line 8-8 in FIG. 2.

1 Claim, 7 Drawing Sheets# US D1,093,328 S
